HEEL BREASTING MACHINE

Nicholas L. Gulliford, deceased, late of Peabody, Mass., by Archibald T. Gulliford, administrator, Lynn, Mass., assignor to Gulliford Wood Heel Company, a firm composed of Archibald T. Gulliford and Pearce H. Gulliford, both of Lynn, Mass.

Application May 25, 1931, Serial No. 539,884

21 Claims. (Cl. 12—47.1)

This invention aims to provide a simple automatic heel grooving machine and in the accompanying drawings there is shown merely for illustrative purposes one embodiment of the invention, wherein:

Fig. 1 is a plan view of an improved heel block grooving machine constructed in accordance with this invention;

Fig. 2 is a perspective view of the heel blank;

Fig. 3 is a perspective view of a heel block after the heel breasting operation has been completed;

Fig. 4 is a section partly in elevation taken on the line 4—4 of Fig. 1;

Fig. 5 is a detail section on the line 5—5 of Fig. 4;

Fig. 6 is a diagrammatic view of the work and cutter blade, a portion of said cutter blade being shown in full lines in one operative position relatively to the work and in dotted lines in a different adjusted position relatively to said work;

Fig. 7 is a detail elevation of the work clamping device viewed in the direction of the arrow a, Fig. 1;

Fig. 8 is a detail view of the work clamping device shown in Fig. 7 and advanced one step from that shown in said figure;

Fig. 9 is a detail view similar to Fig. 8 but with the work clamping device shown released;

Fig. 10 is a detail section on line 10—10 of Fig. 8;

Fig. 11 is a detail plan section taken on line 11—11 of Fig. 8;

Fig. 12 is a detail sectional elevation taken on line 12—12 of Fig. 1;

Fig. 13 is a plan section on line 13—13 of Fig. 12;

Fig. 14 is a detail view partly in section showing the chain tightener;

Fig. 15 is a detail section on line 15—15 of Fig. 1;

Fig. 16 is a detail view of the means for adjusting the ring for carrying the clamping members;

Fig. 17 is a detail section on line 17—17 of Fig. 1; and

Fig. 18 is a detail plan view of the gauge for automatically positioning the heel blocks radially on the work carrier.

In the particular embodiment of the invention selected for purposes of illustration and shown in the drawings, there is shown a continuously revolving work carrier consisting, for example, of a ring 2 having an inside diameter of appropriate size to correspond in curvature with that required for the heel breast. This carrier 2 is rotatably supported by an annular table 4 suitably supported by legs 6.

The table 4 is annularly grooved in its upper

face at 8 (see Figs. 4 and 15) to receive correspondingly curved flanges 10 constituting annular guides for guiding said ring 2 and members 10 during the feeding and shaping of the work. The ring 2 is hollowed out at 3 to contain a ring gear 12 carried by the ring 10, said ring gear having gear teeth 14 formed upon its inner face to mesh herein with the teeth 16 of a spur pinion 18 housed interiorly of the combined table 4 and carrier ring 2 (see Fig. 1).

A shaft 20 secured to rotate with the spur pinion 18 is preferably journaled to rotate in a bracket 22 secured to the under part of the table 4 and is enlarged to form a housing 24 for encasing gearing, herein consisting of a worm gear 26 secured to the shaft 20 and meshing with a worm 28 arranged to rotate with a shaft 30 (see Fig. 17). The worm gear 28 and shaft 30 are herein shown driven by a pulley 32, belt 34 and driving pulley 36 from the motor shaft 38, whereby the desired decreased speed may be imparted to the work table 4.

The motor 40 from which the train of reducing gears driven by the shaft 38 receives its motion is preferably secured to an appropriate part of the machine frame, desirably beneath the table 4 (see Fig. 17).

The carrier ring 2 is shown as having a flat top to receive or support the base b of the heel blank B (see Fig. 4), and after the blanks have been properly positioned upon said ring, as will be more fully described, they are clamped in positions with their breast surfaces directed toward the inner face 42 of said ring 2, after which clamping means are brought into action firmly to clamp the blanks successively in positions for cutting or shaping operations. To this end there is employed a clamping member 44 having a roughened blank engaging face 46 to engage the bottom face of the heel blank.

The clamping member 44 is mounted in a clamping head 48 to move up and down bodily with said clamping head in the absence of a heel blank, but when the roughened end 46 of said clamping member engages the heel blank at too high a point the said clamping member is adapted to yield slightly or the extent to which said heel block is set above the normal height of the heel. To provide for the above there is shown herein means comprising a cushioning spring 50 inserted in said clamping member and which allows for the necessary yielding of the clamping member. To effect the clamping action of the clamping member automatically there is provided herein a pillow block 52. A cam member 55

54 is also provided which is rotatably mounted in said pillow block and engages a cam follower portion 55 of the clamping plunger. The follower 55 is arranged to be operated at the proper times by said cam during the rotation thereof, automatically to move the clamping member into engagement with the heel blank so as to clamp the work while the cutter is operating thereon. The cam member 54, shown most clearly in Figs. 10 7 to 10 inclusive, is so designed and operated that rotation of said cam imparts a step by step movement to the clamping member, and this step by step action is desirably instituted by means of a star-like wheel member 56 secured to one end of 15 the cam 54 so as to rotate as one with said cam.

Each pillow block 52 is carried by a ring 58 mounted at a desired distance above the work supporting member 2 in adjusting devices hereinafter described, said adjusting devices being spaced circumferentially about said supporting member so as to provide uniform support therefor.

In the present example, the ring 58 is adjustable vertically upon a series of upright guide rods 60, shown most clearly in Fig. 12, said guide rods being spaced about and rigidly mounted in said work support 2 by screw threads 62 formed at their ends which are screwed into tapped holes 63 formed in the upper face of said work support. Shoulders 64 formed upon said rods engage the upper face of said work support and maintain said rods at a predetermined height relatively to said rods. Springs 66 encircle the guide rods 60 and yieldingly support said ring 35 58 upon said rods. The upper ends of the guide rods 60 are further threaded at 68 and are engaged by nuts 72 made in the form of sprocket wheels which engage spacing collars 74 arranged between the ring 58 and said sprockets.

40 Encircling the sprockets 72 and meshing with the teeth 73 of said sprockets is an endless sprocket chain 76, upon the revolving of which by any suitable means, for example a wrench (not shown), the various sprockets 72 are simultaneously rotated and cause the threaded studs 60 to be moved vertically in one direction or the other to effect a similar movement of the ring 58 in constantly parallel relation with the work support 2. The springs 66 raise the ring 58 when the sprockets are rotated in one direction, and are compressed when said ring is lowered by a reversal of movement of said sprockets under the action of the screw threads 62. Attached to one of the sprockets of said series, herein the sprocket 55 72, is a hollow hub 78 provided with a squared end 80 to which said wrench may be fitted.

60 By reason of the foregoing construction the clamping members 44 mounted upon said ring 58 at predetermined points may be adjusted at the proper times in the operation of the machine to engage the heel block that is to be operated upon by the work member, as said carrier ring moves past said work member.

To render the machine automatic the clamping members are arranged to be set down automatically as said work carrier is revolved, so that no time will be lost between successive operations. To this end there is provided the step-by-step motion mechanism for operating said clamping device, hereinbefore mentioned, which preferably embodies a star wheel 82, which, as herein shown, has four arms 84, one face of each arm being cam-shaped as shown at 86. Cooperating with the arms 84 are cam rollers 88 two of which are carried upon a bracket 90 secured by screws 92 to

the stationary bed of the machine. In the present example there are two such brackets, as shown in plan view at B and B'. The bracket B is arranged near and at one side of the cutting member 94, whereas the second bracket carrying cam rollers 88 is positioned near the opposite side of said cutting member, and these cam rollers being placed in the positions shown, for example in Figs. 1, 7, 8 and 9, and arranged to engage the arms a, b, c and d, will be successively kicked around by said cam rollers 88 as said star wheels are revolved about the machine.

Each arm 84 of a star wheel will rotate its cam shaft 54 one quarter of a turn, and the cam rollers 88 are so arranged that each of these arms 15 will be moved once during each revolution of the work carrier and thereby effect one complete rotation of its star wheel.

As a clamping device approaches the work cutter 94 it will be left in such a position by the previous rotation of the star wheel that it will just barely clear a heel blank upon the table 2, whereupon the first kick of the star wheel by one of said cam rollers will cause the roughened end 46 of said clamping member to engage the bottom 25 face of the heel of the blank positioned in the machine ready for operation. The next kick of said star wheel by the next cam roller to be engaged thereby merely effects an idle movement of the cam 54, for example approximately along 30 the rest 96. This step does not change the position of the clamping member 46, but merely places the cam in a position so that when the next cam roller is engaged by the arm c, said clamping member 46 will be raised to release the 35 heel blank held thereby and permit the heel that was finished by the preceding cutting operation to be ejected from the machine. The next movement of a star wheel, namely that caused by the engagement of the arm d with the next abutment, will cause the cam 54 to idle without effecting any movement of the clamping member 44, thereby placing said clamping member in position to be moved into engagement with the next end block to be operated upon.

45 As the work carrier 2 is circular in form and endless, said carrier will be moved continuously in one direction permitting the heel blanks W to be placed relatively close together, thereby eliminating all lost time in the operation of the machine and greatly speeding up the operation of the present machine over other machines now in use for this purpose. To facilitate the placing of the heel blank in alignment with the clamping members 44, there is desirably provided a gauge 50 93 adjustably secured in approximately radial relation to said work carrier and slightly at the left of each clamping member 44, so that when the block W is placed against the radial face of said gauge 93, said blank will be positioned approximately centrally of the radial axial line of said blank. The gauge 93 is herein shown adjustable so that it may be moved to maintain blocks of different widths in central positions relatively to the axis of the cutter 94 when the heel blank is passing that point. Cooperating with the gauge 93 is a circumferentially arranged work guide 100 (see particularly Figs. 1, 15 and 18). The guide 100 extends circumferentially of the carrier 2 a distance corresponding 70 to a plurality of heel block positions, and in advance of the work cutting member 94, said guide being pivoted at 102 upon a bracket 104 secured to a fixed part of the frame near the inner edge of said carrier 2.

The outer edge 106 of the guide 100 is desirably approximately concentric with the adjacent edge 108 of said work carrier 2, but is adjustable about the axis of the pivot 102 so that the heel blocks, which are carried along by the carrier by means of the gauges 98, will be engaged by the outer face 106 of said guide 100 and moved radially to a position properly to align it with its respective clamping member. The heel blocks are naturally of varying designs and shapes, consequently the devices for positioning said blocks relatively to their clamping members must be adjusted occasionally to fit the particular heel block to be acted upon, and to this end the guide 100 is provided with a downwardly extending lug 110, and engages at its lower end the upper end 111 of an adjusting screw 112 mounted in a fixed part of the frame of the machine. A second adjusting screw 113 has a screw-threaded stem 114 for fitting a tapped hole in another fixed portion of said machine, and extends radially into contact with the downwardly projecting lug 110. A spring 115 is mounted between a fixed abutment 116 of the frame and said downwardly projecting lug 110, said spring normally tending to swing said guide 100 outwardly about its pivot 102. The adjusting screw 113 is arranged to be moved in or out radially of said carrier and during such movements to swing the guide 100 about its pivot 102 to adjust the position of said guide, and to place the end 117 thereof in the desired relation to the work cutter, whereby the blocks W will leave the positioning devices at the exact location desired for action upon it by the cutter head. The adjusting screw 112 is provided for securing and locking the guide 100 in its properly adjusted position.

To compensate for wear and stretch in the endless chain 76 provided for the adjustments of the studs which carry the ring 58, there is desirably provided an idler pulley 118 (see Figs. 1 and 14), which is rotatably mounted upon an eccentric head 119 of a bracket 119' (see Fig. 14), secured by a stud 119² and a nut 119³ in adjustable relation upon the ring 58, and being eccentrically mounted upon said stud 119² whereby said idler pulley may be varied radially of the carrier ring 2 between two adjacent sprockets 72 and thereby take up slack in said chain 76.

The spring 50, hereinbefore referred to, is adapted to yield only slightly and has nothing to do with the return of the clamping member to its upper position except in so far as the said slight yielding is concerned, but herein there are provided additional yielding means in the form of springs 120, three of which springs are circumferentially spaced as shown in Figs. 10 and 11 in recesses formed in the member 48 and interposed between a shoulder or seat 121 near the lower side of the ring 58, and a flange 122 at the upper end of the movable member 44. By the foregoing arrangement the upper part or cam follower 55 and the clamping member 44 with the spring 50 between them move in unison under the impelling action of the cam 54, and when said clamping member 44 engages the heel block W (see Fig. 10), the spring 50 will be more or less compressed according to the height of the heel. Normally the upper end of the shouldered portion of the clamping member 44 will seat against the face 123 in the clamping head and will be held in this position yieldingly by the springs 120, but when said clamping member is

depressed by the cam 54 the springs 120 will be compressed as shown in said Fig. 10, through the spring 50 which latter will be compressed to a less extent than the springs 120 because larger and stronger.

It will be obvious that much dust will be created around the clamping heads of the device by the cutter head and that it will be desirable to provide means for preventing said dust from working into the crevices between the relatively sliding parts of said clamping head, and to this end means are provided, herein including dust washers which are inserted in an enlarged annular recess 124 in the member 58 containing said clamping members 44.

The clamping member 44 is beveled on opposite sides 125 and 126, one of these bevels, herein the bevel 126, being beveled to a greater degree than the bevel 125, as indicated by the distances e and f (Fig. 10). These bevels provide clearance between the cutting member 94, shown in dotted lines in Fig. 10, and opposite sides of the clamping member 44, that is to say, when the clamping member 44 is turned with its beveled side 126 toward the cutter 94, as in Fig. 10, the latter may be tilted so as to produce a minimum offset or cant to the heel, as indicated at N, Fig. 6, without interfering with the clamping member, and when said clamping member is reversed so as to present the lesser beveled face 125 to the cutter it will produce a heel with a maximum offset or degree of slant, as indicated at i. The machine however is not limited to degrees of bevel shown. To enable the clamping member to be readily changed from one of the foregoing positions to the other, said clamping member 44 has a cylindrical barrel to fit within the clamping head 48 and may be rotated so as to bring one or the other bevel 125 or 126 face to face with the cutting face of the cutter. Oppositely disposed in the flange 122 of the clamping member 44 are two notches 127 and 128 and slidably mounted in said clamping head 48 is a key 129 which may be moved to enter one or the other of the notches 127 and 128 and lock the clamping member from rotating in said clamping head. The key 129 is notched at 130 to assist the operator in moving said key into and out of its notch-engaging or clamping position (see Figs. 8 and 11). A set screw 131 is arranged normally to hold the key 129 in its adjusted positions.

The cutting member 94 is herein arranged to be rotated by means of a motor 132, and said cutter head is capable of being tilted to a plurality of positions hereinbefore mentioned for the purpose of changing the angle of the cut in the breast of the heel as shown in Fig. 3 at 133. For the purpose of changing the angle or degree of cant of the cut with respect to the bottom surface g of said heel (see Fig. 3), the motor 132, which rotates said cutter head, is adapted to be swung into a plurality of angular positions relatively to a horizontal plane. To accomplish this result said motor 132 is mounted upon a segmental frame 134 (see particularly Fig. 4). The center of the arc about which the motor casing 132 and its cutter 94 are arranged to swing is indicated at 135 in Fig. 4, said point being located desirably coincidentally with a point in the periphery of the cutter head 94, and in proximity to the deepest point of the cut to be made by said cutter in the face or breast of the heel block. The segmental frame 134 is provided in its face with a segmental slot 136 through which

extend clamping screws 137, herein arranged on opposite sides of the motor casing 132. Also attached to said motor casing is a segmental rack 138 secured to the side of the motor casing by screws 139, said rack having teeth to engage a worm 140 rotatably mounted in a bearing 141 carried by the segmental frame 134. The worm 140 is herein arranged to be rotated by a hand wheel 142 secured to the worm shaft in a convenient place to be operated from the operator's position at the machine.

In addition to the segmental adjusting means for the cutter the latter is arranged to be moved bodily parallel with the face of the work support 2 and also in a direction perpendicularly to said face. To adjust the cutter head perpendicularly to the face of said support said segmental frame 134 has secured thereto, by means of the screws 137, a double faced plate 143 having tongues 144 arranged to operate in corresponding grooves 145 formed respectively in the faces of the plate 143 and 134. Relative movement is effected between the plate 143 and the frame 134 along the lines of the abutting faces 147 by means, herein including a screw-threaded rod 148, having screw-threaded engagement with the plate 134 in a tapped hole 149. The screw 148 is shouldered down at 150 to form opposed shoulders 151 and 152, between which is arranged a lug 153. The screw 149 has a head 154 to which a wrench may be applied to rotate said screw and produce relative movement between the frame 134 and the plate 143. Screws 155 are provided between the frame 134 and the plate 143 in slots of one of said members to permit said relative movement when said screws are released, said screws being normally tight to hold said plate in stationary relation.

To adjust the cutter 94 in a direction approximately parallel with the face of said work support 2 there are provided cooperating tongues and grooves 156 and 157 to cause the engaging surfaces represented by the line 158 to be properly guided, and this relative movement is herein effected by means of a screw 159, which is rotatably arranged between abutting shoulders 160 and 161 engaging a lug 162, the threaded end of said screw 159 having engagement with the slide 143. Screws 163 between the plates 143 and 162 and working in slots 164 in one of said plates are provided for securing said plates in their adjusted positions by the screw 159. In addition to the cutter head 94, which is provided solely for cutting the breast of the heel, there is provided a second work member or cutter 174 (see Figs. 1 and 12). This cutter preferably has straight teeth, and is arranged to engage the lip 165 of the blank (see Fig. 3) and concave said lip on an arc equivalent to one struck from the center of said work support. The cutter 174 is secured by a nut 166 to the arbor 167 of a motor mounted in the casing 168 (see Fig. 12). The motor arbor 167 is rotatably mounted in a bearing 169, the latter being eccentrically mounted in motor casing 168 by a clamping screw 170, said motor casing being mounted upon the stationary part 4 of the work carrier support.

The cutter 174 is arranged to rotate about an axis approximately vertical with its cutting edge engaging the lip surface 165 of the heel, and in order to adjust said cutter to conform to the position of the block on the work carrier, the screw 170 is released and the eccentric 171 carrying the bearing 169 is rotated by means of a handle 172 to bring the axis of the motor arbor

167 to the right location relatively to the heel block.

The invention is not limited to the specific embodiment shown.

What is claimed is:

1. A machine for shaping heel breasts comprising a heel blank holder, a rotating cutter head, and means to rock said cutter head about a selected point in the heel breast to vary the inclination of the heel breast. 10

2. A machine for shaping heel breasts having, in combination, a heel blank holder for bodily moving a heel blank about an axis of rotation, a rotary cutter for operating upon said blank as it is so moved, the axis of rotation of said cutter and the axis of rotation of said heel blank intersecting, and means for adjustably tilting the axis of rotation of said cutter about an axis normal to the plane defined by said intersecting axes and approximately tangent to the portion of said cutter which forms the deepest part of the heel breast. 20

3. A machine for shaping heel breasts having, in combination, a heel blank holder for bodily moving a heel blank about an axis of rotation, a rotary cutter for operating upon said blank as it is so moved, the axis of rotation of said cutter and the axis of rotation of said heel blank intersecting, means for adjustably tilting the axis of rotation of said cutter about an axis normal to the plane defined by said intersecting axes and approximately tangent to the portion of said cutter which forms the deepest part of the heel breast, and means for adjusting said cutter relative to said holder for varying the position of the deepest part of the heel breast. 30

4. In combination, a heel blank holder, a cutter head, said holder being arranged to move a heel blank past said cutter head with the vertical axis of the heel describing a curved surface, 40 means to effect rotation of said cutter head about its own axis, and means to tilt said cutter head about an axis parallel with the seat of said heel blank to vary the inclination of the heel breast.

5. In an apparatus of the character described, 45 a heel blank support, means to secure the heel blank to said support, a cutter head, means relatively to move said cutter head and said support to form a breast which throughout is concave in horizontal planes of the heel, and means to vary 50 the position of said cutter head transversely of said work support to vary the depth of the concavity of said heel breast.

6. A heel grooving machine comprising, in combination, a heel blank support, a cutter head, 55 means relatively to move said heel blank support and said cutter head to form a heel breast which throughout is concave in horizontal planes of the heel, means to vary the position of said cutter head toward and away from the breast of the 60 heel to vary the depth of the breast concavity, and means to vary the position of said cutter head relatively to said heel blank to vary the location of the deepest point of the heel breast relatively to the heel lip. 65

7. A heel grooving machine comprising a rotary work support, means for clamping heel blanks to said work support, a rotary cutter arranged to operate upon the faces of said blanks opposed to the axis of rotation of said support for breasting 70 said blanks, and means to adjust said rotary cutter relative to said support to a plurality of different angular positions relatively to said work support to vary the angle of the breast of the heel.

8. In combination, a heel blank support ar- 75

- ranged to revolve about an axis, a rotary cutter head for breasting the faces of heel blanks opposed to said axis, and means to move said cutter head radially of said work support to vary the 5 depth of said cut.
9. A machine for grooving heels comprising a work support arranged to revolve about a vertical axis, means to clamp the work on said support, a rotary cutter head, means relatively to 10 rotate said cutter head and said work support to concave the breast of the heel transversely in a plane parallel with the seat of said heel, and means to tilt the cutter head radially of said work support to vary the inclination of the heel breast.
15. 10. A machine for breasting heels comprising a heel blank holder, a cutter head, means relatively to move said heel blank holder and said cutter head to concave the heel breast in horizontal planes of the heel, and means to tilt said cutter head to vary the inclination of said heel breast.
20. 11. A machine of the class described comprising a revolving work carrier, cutter means, means relatively to move said work carrier and cutter means to shape the work, and means automatically to clamp and release the work on said work carrier including a star wheel mechanism operated during the rotation of said work carrier.
25. 12. A machine of the class described comprising a revolving work carrier, cutter means, means relatively to move said work carrier and cutter means to shape the work, and means automatically to clamp and release the work on said work carrier including star wheel mechanism on said revolving work carrier, and normally stationary means for 30 operating said star wheel mechanism.
35. 13. In a heel breasting machine, a circular heel carrier, heel clamping means on said carrier, a cutter arranged within said circular carrier adapted to be tilted to vary the angle of the heel breast with respect to the vertical axis of said heel, a clamping member for said heel, and means 40 operated by said carrier automatically to operate said clamp to secure the heel blank to said heel carrier.
45. 14. In a heel breasting machine, a heel holder, a rotatable heel clamping member, a cutter, means relatively to move said cutter and said heel holder to breast said heels, and means to adjust said cutter to different angular positions relatively to said heel, said clamping member having its opposite faces differently beveled respectively to 50 clear said cutter during the breasting operation in different positions of angular adjustment of said cutter.
55. 15. A machine of the character described having, in combination, a rotary holder for heel blanks arranged to move the blanks in an arcuate path with their breast portions facing the axis of rotation of said holder, a rotary cutter for operating upon said blanks for grooving the heel breasts, said cutter being within the orbit followed by said holder and having its axis lying in a 55 plane which includes the axis of said holder, and means for adjustably tilting the axis of said cutter in said plane.
16. A machine of the character described having, in combination, a rotary holder for heel blanks arranged to move the blanks in an arcuate path with their breast portions facing the axis of rotation of said holder, a rotary cutter for operating upon said blanks for grooving the heel breasts, said cutter being within the orbit followed by said holder and having its axis lying in a 60 plane which includes the axis of said holder, means for adjustably tilting the axis of said cutter in said plane, and means for adjustably moving it in said plane in directions parallel with the axis of said holder and perpendicularly thereto.
17. A machine of the character described having, in combination, a heel blank holder mounted for rotation about a vertical axis, a rotary cutter for breasting the blank having an axis in a vertical plane which includes the axis of said holder, and means for adjustably tilting said axis of said cutter in said plane about a horizontal axis normal to said plane and approximately tangent to that portion of the face of said cutter which forms the deepest part of the breast.
18. A machine of the character described having, in combination, a heel blank holder mounted for rotation about a vertical axis, a rotary cutter within the orbit followed by the heel blank when rotated by said holder, said cutter adapted to operate upon the blank for breasting it and having its axis in a vertical plane which includes the axis of said holder, and means for adjustably 30 tilting said axis of said cutter in said plane for varying the inclination of the heel breast.
19. In a machine of the class described, a circular work carrier, means to clamp the work against the face of said work carrier, a lip trimming cutter arranged within said circular work carrier, and means to adjust said cutter radially of said work carrier to vary the depth of cut.
20. In a machine of the class described, a circular work carrier, means to clamp the work against the face of said work carrier, a motor driven lip trimming cutter arranged within said circular work carrier, and means to move said cutter transversely of said work carrier and radially thereof to vary the depth of cut.
21. In combination, an annular heel blank holder arranged to carry heel blocks in a circular path with their seats arranged horizontally, a cutter head, means to rotate said cutter head about its axis, and means to tilt said cutter head to bring its axis of rotation in different angular positions relatively to the axis of movement of said heel blocks to vary the inclination of the breasts of the heel blocks.

ARCHIBALD T. GULLIFORD, 60
Administrator of the Estate of Nicholas L. Gulliford, Deceased.
